UNITED STATES PATENT OFFICE.

PETER ZUNISH, OF JENKINS, KENTUCKY.

DESIGN FOR A CAN-OPENER.

52,156.

Specification for Design.

Patented July 2, 1918.

Application filed August 24, 1915. Serial No. 47,150. Term of patent 3½ years.

To all whom it may concern:

Be it known that I, PETER ZUNISH, a citizen of the United States, residing at Jenkins, in the county of Letcher and State of Kentucky, have invented a new, original, and ornamental Design for Can-Openers, of which the following is a specification, reference being had to the accompanying drawings, forming a part thereof.

The ornamental design for a can opener, as shown.

PETER ZUNISH.

Witnesses:

J. E. HUTH,
JOHN D. W. COLLINS.
